UNITED STATES PATENT OFFICE.

GEORGE E. DAVENPORT, OF CAMDEN, NEW JERSEY.

REPEATING APPARATUS FOR TALKING MACHINES.

Application filed October 25, 1920. Serial No. 419,253.

To all whom it may concern:

Be it known that I, GEORGE E. DAVENPORT, a citizen of the United States, residing at Camden, in the county of Camden and 5 State of New Jersey, have invented certain new and useful Improvements in Repeating Apparatus for Talking Machines, of which the following is a specification.

One object of my invention is to provide 10 improved apparatus of a durable character which will be effective after the playing of a record to automatically cause the record to be repeated.

Another object is to so make my improved 15 apparatus that it can be readily applied to a talking machine and will be adjustable to suit records of different sizes.

These objects, and other advantageous ends which will be described hereinafter, I 20 attain in the following manner, reference being had to the accompanying drawings in which

Figure 1 is a fragmentary top plan view 25 of my improved apparatus illustrated in the position it assumes when mounted upon a talking machine, certain of the elements of the talking machine being illustrated in dot-and-dash lines,

Figure 2 is an elevation looking in the 30 direction of the arrow α in Figure 1; certain of the parts being illustrated in section,

Figure 3 is an enlarged fragmentary plan view of certain of the parts shown in Figures 1 and 2 and illustrating some of the 35 parts in dotted lines,

Figure 4 is a fragmentary section taken on the line 4-4 of Figure 2 and drawn on an enlarged scale, and

Figure 5 is an end elevation, partly in 40 section, showing certain of the parts of my invention.

Referring to the drawings, 6 represents the top of a talking machine cabinet above which the record turntable 7 is mounted; 45 said turntable being adapted to be rotated by a center post or shaft 8 in the usual manner. A tone arm 9, which may be of any construction capable of swinging in a vertical and horizontal plane, has a sound box 50 10 thereon adapted to co-act with a record, placed upon the turntable 7, in the usual manner.

A bracket 11 is secured to the top 6 of the talking machine cabinet at one side of 55 the turntable 7 and this bracket has an extension 12 providing a pivot 13 for a swing-

ing beam 14; the pivot 13 being positioned between the opposite ends of said beam as clearly shown in Figure 2. A suspension rod 15 is connected to the end 16 of the 60 beam 14 and has a weight 17 thereon adapted to move the hooked end 18 of the beam upwardly under certain operating conditions hereinafter described. The weight 17 may be positioned within the cabinet and the 65 top of the cabinet may be provided with a slot 18 to permit the rod 15 to extend through the top 6 into the cabinet so that the weight will not be exposed to view.

A frame 19 has one end pivoted at 20 to 70 the bracket 11; said frame having a worm 21 thereon which is connected to a friction disk roller 22 adapted to frictionally engage the under surface of the turntable 7 as shown in Figure 2 so that when said friction 75 roller 22 is in engagement with the turntable, the worm 21 will be rotated. The frame 19 has upwardly extending arms 23 which form the bearing for a shaft 24 to which is keyed a worm wheel 25; said worm 80 wheel 25 meshing with the worm 21.

A crank 26 is secured to the shaft 24 and has a crank pin 27 pivotally connected to the lower end of a link or pitman 28. The upper end of the link 28 is pivoted at 29 85 to a head block 30 which is vertically slidable in a guideway 31 formed in the top of the bracket 11. The rear part of the link 28 immediately adjacent the head block 30 has a recess 32 therein, the inner end of 90 which is beveled as shown at 33 in Figure 4. The head block 30 has a pin 34 freely slidable therein, the rear end of which is adapted to be engaged by a plate spring 35 which is secured to the head block 30. The spring 95 35 has a portion which extends above the top of the head block 30; said portion being provided with a slot 36 adapted under certain conditions to engage a pin 37 on the beam 14. The plate spring 35 normally 100 tends to move the pin 34 toward the link 28 and when the recess 32 is entirely in front of the pin 34, the forward end of the pin 34 will be moved by the spring 35 into the recess 32 and this movement of the 105 spring will cause its upper end to move out of engagement with the pin 37 on the beam 14. A swinging movement of the link 28 on its pivot 29, however, will cause the beveled part 33 to push the pin 34 rearwardly 110 and also move the spring 35 rearwardly and place it under tension. The top of the

spring 35 is preferably bent forwardly as shown at 38 in Figures 2 and 5 to permit the pin 37 to flex the top end of the spring 35 forwardly when the spring 35 moves upwardly as will hereinafter be described so that the pin 37 can enter the slot 36 to assume the position illustrated in Figures 2 and 5.

The friction wheel 22 is held in engagement with the turntable 7 due to the connection of a spring 39 which is attached to the frame 19 and to a lug 40 on the bracket 11. A latch lever 41 is pivotally connected at 42 to the bracket 11 and has a torsion spring 43 adapted to move the lower arm 44 of the lever 41 into engagement with the frame 19 under certain conditions and move the friction roller 22 downward out of engagement with the turntable 7. The upper arm 45 of the latch lever 41 has a hook 46 thereon adapted to engage over a shoulder 47 on a latch 48; said latch being pivoted at 49 to the beam 14 and being located adjacent a side surface 50 of the bracket 11. A trip lever 51 is pivoted at 52 to the bracket 11 and has a shoulder 53 on its lower arm 54 which is adapted under certain conditions to engage over the top 55 of the frame 19 at a position remote from its pivot 20. The upper arm 56 includes a section 57 adjustably pivoted thereto at 58 as shown in Figure 2. The beam 14 is adapted to extend under the tone arm and the parts of my invention are operative after the playing of the record to lift the tone arm through the medium of the beam 14; the beam 14 slanting so as to cause the tone arm to slide downwardly toward the pivot 13 and then be lowered with the reproducing needle in the outer grooves of the record. Figure 2 shows the parts in the position which they assume just prior to the time in which the reproducing needle will be lowered into the outer grooves of the record.

A clamping band 59 is secured to the part 60 of the tone arm which receives a pivotal movement in a horizontal plane and said clamping band 59 has a projection 61 which is connected to a link 62. The link 62 as clearly shown in Figure 1 is connected to a trip arm 63; said trip arm being pivotally connected at 64 between its ends to the pivot plate 65 which is secured to the top 6 of the cabinet. The end 66 of the trip arm 63 has an adjusting screw 67 extending therethrough; the adjusting screw being positioned, when the tone arm is moved inwardly, to actuate the trip arm 63 through the medium of the projection 61 and link 62 to push the arm 44 upwardly out of engagement with the frame 19 and thereby permit the friction roller 22 to again engage the turntable 7. It will be noted that the upper arm 56 of the trip lever 51 is offset so that the weight of the upper arm normally tends 65 to move the lower arm 54 to cause the shoul-

der 53 to move over the top 55 of the frame 19 when the frame 19 has been lowered due to the action of the spring 43 on the latch lever 41.

Considering that the crank pin 27 is moving downwardly, as shown in Figure 2, to move the beam 14 downwardly due to the connection between the link 28, head block 30, spring 35 and pin 37, the tone arm, having been previously swung to its outermost position, will be lowered to present the needle to the outer grooves of the record. When the crank pin 27 reaches its lowermost position the hook 46 of the latch lever 41 will be moved over the shoulder 47 of the latch 48 and the arm 44 of the latch lever will move down into engagement with the frame 19 and swing the frame 19 against the action of the spring 39 to move the friction roller 22 down out of engagement with the turntable 7. The section 57 of the trip lever 51 being free of the tone arm will allow the shoulder 53 of the arm 54 to move over the top 55 of the frame 19 and thereby prevent the frame 19 from moving upwardly until the tone arm again strikes the section 57 which will not occur until the next repeating action.

After the record has been completely played, the end 66 of the trip arm 63 will have been actuated so as to move the adjusting screw 67 into engagement with the arm 44 of the latch lever 41 and the latch lever will then be swung against the action of the spring 43 to pull the hooked end 46 out of engagement with the shoulder of the latch 48 and to move the end 44 of the lever 41 away from the frame 19. The pin 34 having previously moved into the recess 32 so as to free the pin 37 of the spring 35, the counterweight 17 will swing the beam 14 on the pivot 13 and will lift the sound box out of engagement with the record and, due to the slant of the beam 14, the tone arm will slide downwardly thereon until it engages and moves the section 57 of the trip lever 51 and will then move the shoulder 53 away from the top of the frame 19. The frame then being released will be moved by the spring 39 to cause the friction roller 22 to again engage the turntable and thereby actuate the worm 21 to turn the crank and to thereby effect the movement of the head block 30 and spring 35 upwardly so as to cause the pin 37 to engage through the slot 36 as previously described and a continued movement of the crank will cause the beam 14 to be moved downwardly having been caught by the spring 35 and the sound box will be lowered so as to cause its reproducing needle to again engage the outer grooves of the record to repeat the playing of the same.

By turning the adjusting screw 67, the timing of the release of the latch lever can be varied to suit different requirements as to the size of the playing portion of a record,

and the section 57 of the trip lever 51 can also be swung into various positions so as to vary the position at which the release of the frame 19 by the arm 54 will be accomplished.

5 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what 15 I claim as new and desire to secure by Letters Patent is:—

1. The combination in a talking machine, including a tone arm having reproducing means connected therewith, of repeating 20 apparatus, including a beam for engagement with the tone arm; means, adjustable as to position, automatically operative to move the beam into an inclined position to cause the tone arm to be raised and to slide 25 thereon, and means automatically rendered operative by the tone arm during the sliding movement to effect a lowering movement of the beam to allow the reproducing means to engage the record, substantially as 30 described.

2. The combination with a talking machine including a tone arm having reproducing means connected therewith, of repeating apparatus including a beam; means for 35 swinging the beam into a slanting position to cause the tone arm to be raised and slid into a position with the reproducing means over the initial playing portion of the record; and means operative by a movable 40 portion of the talking machine to effect the lowering movement of the portion of the beam supporting the tone arm to permit the reproducing means to move into engagement with the initial playing portion of 45 the record, substantially as described, said latter operative means including a portion movable by the tone arm during said sliding movement thereof to effect connection of said operative means with said movable portion 50 of the machine.

3. The combination with a talking machine including a rotatable turntable, a tone arm, and reproducing means connected to the tone arm, of a beam for engaging under 55 the tone arm; means operatively connected to said tone arm and movable to effect the swinging of said beam into a slanting position to raise the reproducing means and to cause said tone arm to slide on the beam to 60 present the reproducing means at a position over the initial playing portion of a record on said turntable; and means having a portion for contact with and movable through the medium of movement of said 65 turntable to effect the downward movement

of said beam to permit said reproducing means to engage the initial playing movement of the record; substantially as described.

4. The combination with a talking machine including a tone arm having reproducing means connected therewith, of repeating apparatus including a beam; means for swinging the beam into a slanting position to cause the tone arm to be raised and slid 75 into a position with the reproducing means over the initial playing portion of the record; and means operative by a movable portion of the talking machine to effect the lowering movement of the portion of the beam supporting the tone arm to permit the reproducing means to move into engagement with the initial playing portion of the record, said operative means including a reciprocating device adapted to automatically 80 engage and swing said beam downwardly; substantially as described.

5. The combination with a talking machine including a tone arm having reproducing means connected therewith, of repeating apparatus including a beam; means for swinging the beam into a slanting position to cause the tone arm to be raised and slid into a position with the reproducing means over the initial playing portion 90 of the record; means operative by a movable portion of the talking machine to effect the lowering movement of the portion of the beam supporting the tone arm to permit the reproducing means to move into engagement with the initial playing portion of the record, said operative means including a reciprocating device adapted to automatically engage and swing said beam downwardly; substantially as described.

6. The combination with a talking machine including a tone arm having reproducing means connected therewith, of repeating apparatus including a beam; means for swinging the beam into a slanting position to cause the tone arm to be raised and slid into a position with the reproducing means over the initial playing portion of the record; means operative by a movable portion of the talking machine to effect the 100 lowering movement of the portion of the beam supporting the tone arm to permit the reproducing means to move into engagement with the initial playing portion of the record, said operative means including a reciprocating device adapted to automatically engage and swing said beam downwardly; substantially as described.

7. The combination with a talking machine including a tone arm having reproducing means connected therewith, of repeating apparatus including a beam; means for swinging the beam into a slanting position to cause the tone arm to be raised and slid into a position with the reproducing means over the initial playing portion of the record, said operative means including a reciprocating device adapted to automatically engage and swing said beam downwardly; substantially as described.

- sition to cause the tone arm to be raised and slid into a position with the reproducing means over the initial playing portion of the record; and means operative by a 5 movable portion of the talking machine to effect the lowering movement of the portion of the beam supporting the tone arm to permit the reproducing means to move into engagement with the initial playing portion 10 of the record, said operative means including a crank and a reciprocating device connected to said crank and adapted to engage a part of said beam to cause said beam to be lowered; substantially as described.
- 15 8. The combination with a talking machine including a tone arm having reproducing means connected therewith, of repeating apparatus including a beam; means for swinging the beam into a slanting position to cause the tone arm to be raised and slid into a position with the reproducing means over the initial playing portion 20 of the record; means operative by a movable portion of the talking machine to effect the lowering movement of the portion of the beam supporting the tone arm to permit the reproducing means to move into engagement with the initial playing portion 25 of the record, said operative means including a reciprocating device having a resilient portion adapted to automatically engage and swing said beam downwardly; substantially as described.
- 30 9. Apparatus of the character described including a pivoted beam for engagement under the tone arm of a talking machine; a pivoted frame having a friction roller for engagement with the turntable of the talking machine; means for holding the friction roller in connection with the turntable; actuating means on said frame in connection with said roller; means operated by 35 said actuating means; a crank connected to said operated means; a link connected to said crank; means providing a guideway; a member slidably in the guideway and pivotally connected to said link; a
- 40 spring connected to said member; and a pin slidably mounted in said member, said link having a recess therein adapted, upon rotation of said crank, to register with said pin, said beam having a projecting part, said pin being operative, when the link is moved, to cause the pin to be moved out of said recess and to move said spring
- 45 into connecting position with said connecting part of the beam whereby upon further rotation of said crank the beam will be lowered; substantially as described.
- 50 10. The combination with a talking machine including a tone arm having reproducing means connected therewith, of repeating apparatus including a beam; means for swinging the beam into a slanting position to cause the tone arm to be raised and slid into a position with the reproducing means over the initial playing portion 55 of the record; and means operative by a movable portion of the talking machine to effect the lowering movement of the portion of the beam supporting the tone arm to permit the reproducing means to move into engagement with the initial playing portion 60 of the record, said operative means including a reciprocating device having a resilient portion adapted to automatically engage and swing said beam downwardly; substantially as described.
- 65 11. Apparatus of the character described including a beam adapted to be positioned under the tone arm of a talking machine; means for swinging said beam into a slanting position to raise said tone arm and to cause the latter to slide along the beam; a trip lever movable by said tone arm during its sliding movement; and means for effecting a lowering movement to the tone arm-supporting portion of the beam and 70 rendered operative by said movement of the trip lever; substantially as described.
- 75 12. Apparatus of the character described including a beam adapted to be positioned under the tone arm of a talking machine; means for swinging said beam into a slanting position to raise said tone arm and to cause the latter to slide along the beam; a trip lever movable by said tone arm during its sliding movement; and means for effecting a lowering movement to the tone arm-supporting portion of the beam and 80 rendered operative by said movement of the trip lever; substantially as described.
- 85 13. In testimony whereof I have signed my name to this specification in the presence of two subscribing witnesses.
